UNITED STATES PATENT OFFICE.

RAYMOND B. PRICE, OF MISHAWAKA, INDIANA, ASSIGNOR TO RUBBER REGENERATING COMPANY, A CORPORATION OF INDIANA.

ANTISLIPPING AND ANTIWEARING MATERIAL.

1,162,396.

Specification of Letters Patent.

Patented Nov. 30, 1915.

Application filed January 3, 1912. Serial No. 669,211.

To all whom it may concern:

Be it known that I, RAYMOND B. PRICE, a citizen of the United States, residing at Mishawaka, in the county of St. Joseph, 5 State of Indiana, have invented new and useful Improvements in Antislipping and Antiwearing Material, of which the following is a specification.

My invention relates to the manufacture 10 of anti-slipping and anti-wearing material, adapted for various uses hereinafter to be set forth, and has for its primary object to produce a material wherein the surface exposed will embody textile threads or 15 fabric in such manner or so treated that the same will possess substantially no moisture absorbing qualities, a characteristic heretofore of such material which has rendered its exposure objectionable.

20 Primarily my invention embodies the idea of first water-proofing the textile threads to be used, and then embedding said threads in a body of vulcanized plastic material in such manner that said threads shall be positioned in the material substantially end 25 on. That is to say, said threads will be disposed in their containing material at substantially a right angle to the outer wearing surfaces of said material, so that no 30 amount of wear will alter the character of the surface.

In an application filed by me January 19, 1912, Serial No. 672,261, I have described a process of water-proofing threads which I 35 will prefer to use in treating the threads used with my present invention, but I do not wish to be understood as limiting myself to said method of water-proofing, it being sufficient that they be made non-absorbent of moisture.

In the drawing accompanying this specification wherein I have illustrated two methods of preparing my improved material: Figure 1 is a side elevation of an article embodying the first step in my improved process. Fig. 2 is a transverse sectional view of the same. Fig. 3 is a view similar to Fig. 2 after a further step in the process. Fig. 4 is a sectional elevation of a series of sections 50 assembled for vulcanization into a finished article. Fig. 5 is a plan view illustrating the first step in a modified process. Fig. 6 is a transverse sectional view of the same taken after calendering. Fig. 7 is a perspective of the sections of sheets shown in

Figs. 5 and 6 assembled ready for vulcanization.

In said drawing, referring to Figs. 1 to 4, one method of producing my improved material is illustrated, as follows: Taking as a base a solid core 1 of unvulcanized rubber of any suitable shape in cross section I lay upon two sides of the same diametrically opposite each other threads 2 of waterproofed material and then wind around said core and longitudinal threads another thread 3 of water-proof material, the same being wound with its coils as close together as may be desired, as seen in Fig. 1. The article so formed is then passed between rollers and flattened to substantially the configuration shown in cross section in Fig. 3, thereby producing a flattened sheet having the longitudinal strands lying along each edge thereof. This article is then cut longitudinally 75 and centrally along the line A—A, and produces two similar sections each having projecting from its cut edge the ends of two rows of the threads. Upon now assembling any desired number of these sections with 80 their cut edges uppermost, the same may be united into a homogeneous mass by any suitable vulcanizing operation, and will present a finished article wherein the threads are presented in a continuous plane at the wearing surface end on and extending to the base of the article, where they are anchored by passing around the longitudinal thread or cord in loops. By this construction I produce an article wherein the textile 85 threads will always present the same characteristics to the wearing surface, no matter how great the wear thereon may be.

By subjecting the threads employed to the action of a water-proofing medium prior to 95 their use in forming the article, I obviate the objection heretofore found in permitting textile material being exposed at the wearing surface because of its absorptive qualities.

Inasmuch as the longitudinal threads or cords used are intended to act as anchoring members for the spirally wound thread, it will be obvious that they may be replaced by any suitable metallic wire or other material, or may even be dispensed with.

In Figs. 5, 6 and 7 I have disclosed a modification wherein the threads 4 to be used, whether treated or not, are first disposed on the face of a sheet of rubber 5 and

this product is preferably first calendered to embed the threads therein, is then cut transversely into strips to be assembled with the threads disposed end on with respect to 5 the wearing surface, and is finally vulcanized into a homogeneous body.

In this specification heretofore the term "end on" is intended to include any disposition of the threads at any angle or angles 10 to the wearing surface which will present the ends of said threads to said surface, and said threads may be disposed at any angle to each other.

It will be found that, by reason of the 15 comparative isolation of the threads, their capillary action is materially reduced.

It will be understood that in any of the 20 above processes I contemplate employing in place of rubber such substances as gutta percha, balata, and the like, which will, of course be treated in the usual manner pertaining to such materials.

I contemplate by my above processes producing articles adapted for use as the tread 25 of a solid or pneumatic tire, as a matting, as a packing, as a bath brush, as a belt cover, in connection with boot and shoe soles and heels, and for numerous other purposes.

Having thus described my invention, what 30 I claim as new and desire to secure by Letters Patent is:

1. An anti-slipping and anti-wearing material embodying therein a vulcanized body portion and a plurality of independent, adjacent, non-contacting and substantially parallel fibrous threads or cords embedded therein with the ends thereof presented in a continuous plane at the wear surface of said body.

40 2. An anti-slipping and anti-wearing material, embodying therein a vulcanized body portion and a plurality of independent, adjacent, non-contacting and substantially parallel fibrous threads or cords embedded in and looped about one edge of said body portion with the ends thereof presented in a continuous plane at the wear surface of said body portion.

50 3. An anti-slipping and anti-wearing material, embodying therein a vulcanized body portion and a plurality of independent, adjacent, non-contacting and substantially parallel fibrous threads or cords embedded in and looped about one edge of said body portion with the ends thereof presented in a

continuous plane at the wear surface of said body portion, said cords or threads being severally water-proofed.

4. An anti-slipping and anti-wearing material, embodying therein a vulcanized body 60 portion, a plurality of independent, adjacent, non-contacting and substantially parallel fibrous threads or cords embedded in and looped about one edge of said body portion with the ends thereof presented in a continuous plane at the wear surface of said body portion, and means common to a plurality of said threads or cords, interposed between the looped portions thereof and said body portion, whereby each of said 65 cords is anchored with relation to said body portion.

5. An anti-slipping and anti-wearing material, embodying therein a vulcanized body portion, a plurality of independent, adjacent, non-contacting and substantially parallel fibrous threads or cords embedded in and looped about one edge of said body portion with the ends thereof presented in a continuous plane at the wear surface of said body portion, and a fibrous cord or thread 70 common to a plurality of said threads or cords, interposed between the looped portions thereof and said body portion, whereby each of said 75 cords is anchored with relation to said body portion.

6. An anti-slipping and anti-wearing material, embodying therein a plurality of sections 80 united by vulcanization, each section comprising a body portion embodying therein a plurality of independent, adjacent, non-contacting and substantially parallel fibrous threads or cords embedded therein with the ends presented in a continuous plane at the 85 wear surface of said body portion.

90 7. An anti-slipping and anti-wearing material, embodying a longitudinally disposed body portion, separate threads or cords embedded therein and disposed end on toward the wearing surface thereof, and separate 100 threads or cords longitudinally disposed around which the inner portions of said first threads or cords are looped.

In testimony whereof, I have hereunto set my hand in the presence of two subscribing 105 witnesses.

RAYMOND B. PRICE.
